UNITED STATES PATENT OFFICE.

BURNS D. LOCKWOOD, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

RAILWAY-CAR.

1,286,677.

Specification of Letters Patent. Patented Dec. 3, 1918.

Application filed January 29, 1916. Serial No. 75,060.

To all whom it may concern:

Be it known that I, BURNS D. LOCKWOOD, a citizen of the United States, residing at No. 366 Lincoln avenue, Bellevue, in the county of Allegheny and State of Pennsylvania, have invented certain new and useful Improvements in Railway-Cars, of which the following is a specification.

An object of the invention is to provide 10 a car with a movable platform upon which a heavy gun may be mounted, and which, when it is desired to discharge such gun, may be lowered to rest on a concrete or other suitable foundation so that the weight of the 15 platform and the gun and the shock resulting from the recoil of the gun when fired will be sustained by the foundation, and the underframe and trucks of the car relieved of the same.

20 Another object of the invention is to provide a car having a platform which may be carried free of the track rails, or which may be lowered to rest upon a suitable foundation so that the underframe will be relieved 25 of the weight of the table and any load carried thereon.

Another object of the invention is to provide 30 a car having a movable platform which may be lowered to rest on a suitable foundation, and to provide means for bracing said table on its foundation.

Another object of the invention is to provide 35 a car having a movable platform and to provide means for raising and lowering such platform.

With the above and other objects in view the invention resides in the construction, arrangements and combinations of parts hereinafter described and claimed.

40 Referring now to the drawings in which like reference characters refer to like parts, Figure 1 is a plan view of a car embodying the invention. Fig. 2 is a side elevational view of the same, Figs. 3 and 4 are enlarged cross sectional views taken on the lines 3—3 and 4—4 respectively of Fig. 1; Figs. 5, 6 and 7 are diagram, plans, side and sectional views respectively of the car.

Referring now in detail to the drawings, 50 1 indicates the center sill, 2 the side sills, 3 the end sills, 4 the bolsters, all of which are suitably connected together. The center sill may be of any desired construction, but for illustrative purposes it has been shown as 55 comprising a pair of channel members 5

which are preferably spaced apart throughout their length. These members 5 may extend from end sill to end sill, or as shown in the drawings may terminate short of the end sills and have separate draft sills 6 secured to the end thereof.

The side sills 2 may be of any desired construction and preferably extend from end sill to end sill. For illustrative purposes each of these side sills has been shown as comprising a plurality of channel members 7 which are preferably spaced apart throughout their length. The bolster 4 may be of any desired construction, but preferably comprises a plurality of flanged members 8 70 which extend between and are secured to the center and side sills. 9 indicates a bolster cover plate which preferably extends from side sill to side sill and is secured to the bolster members 8, center sill 1 and side sills 2, 75 thus forming a strong connection between such parts of the underframe.

The underframe is mounted on trucks (not shown) in the usual manner, the wheels 10 of which are adapted to travel on the 80 usual track rails 11. At intervals along the railroad track, foundations 12 of concrete or other suitable material may be provided, the use of which will hereinafter be mentioned.

At each end of the car a plate 13 is provided which is secured to the upper portions of the center sill, side sills, end sill and bolster, thus forming a strong connection between the members of the underframe and 85 at the same time forming a platform for trainmen or operators.

Intermediate the end portions of the underframe a movable table or platform 14 is provided upon which a heavy gun or other 90 machinery may be mounted and transported. This table or platform 14 preferably comprises supporting members 15 and 16 which extend in a direction longitudinally of the car. Each of the supporting members 15 100 preferably comprises vertically disposed plates 17 and 18, each of which is provided at its top and bottom edge portions with stiffening members 19 of angle or other suitable sections. The plate 17 is stiffened in 105 a vertical direction by members 20 which may be of angle or other suitable section. These plates 17 and 18 are spaced apart a sufficient distance to permit the side sills 2 to extend therebetween, and are connected 110

together by members 21 and 22 which are secured to the plates by rivets or other suitable means. These plates are further connected together and strengthened by top and bottom cover plates 23 and 24 respectively, the top cover plate 23 being secured to the upper stiffening members 19 and to the member 21, and the bottom cover plate being secured to the lower stiffening members 19. The supporting member 16 preferably comprises vertically disposed plates 25 and 26 each of which is provided at its top and bottom edge portions with stiffening members 27 which may be of angle or other suitable section. These plates 25 and 26 are spaced apart a sufficient distance to permit the center sill 1 to extend therebetween, and are connected together and strengthened by a member 28. These plates are also connected together and strengthened by top and bottom cover plates 29 and 30 respectively, the cover plate 29 being secured to the upper stiffening members 27 and the cover plate 30 being secured to the lower stiffening members 27. If desired the cover plates 24 and 30 may be eliminated and a single plate may be substituted which may cover the entire bottom of the platform or table.

31 indicates a horizontally disposed platform or floor plate which is preferably secured to the supporting members, which plate 31 not only forms the floor of the platform or table 14, but also serves to connect the supporting members 15 and 16, thus strengthening and stiffening the table as a whole.

To further strengthen and stiffen the platform or table 14, members 32 are provided which extend in a direction transversely of the table and connect the supporting members. These members at one side of the longitudinal centerline of the table extend between and are secured to the plate 18 of one of the supporting members 15 and the plate 25 of the supporting member 16, and at the other side of the longitudinal centerline of the table extend between and are secured to the plate 18 of the other supporting member 15 and the plate 26 of the supporting member 16.

At the corners of the platform or table any suitable hand or fluid pressure operated means may be provided for raising and lowering the platform, but for illustrative purposes a screw means 33 has been shown which comprises a threaded member 34 which is secured to the upper portion of the table and with which the threads on the screw member 35 is adapted to engage. The lower end portion of this screw member 35 preferably rests in a socket formed in a member 36 which may be secured between the members 7 of the side sill, while the upper portion of this member 35 extends above the member 34, and is provided with nuts 37 and 38 for holding the screw member 35

against accidental rotation. The upper portion of this screw member is provided with openings 39 through which the end of a bar or other suitable tool may be passed for turning the screw.

It will be noted that the platform or table when in a position to transport a load, as shown in Fig. 2 and in full lines in Fig. 3, that the lower portion of the table will be free of the track rails and that the weight of the table and the load carried thereon will be transmitted to the side sills 2 through the medium of the screw member 35.

To the center sill 1 suitable members 40 are secured with which portions of the table are adapted to engage, thus preventing excessive movement of the table in a direction longitudinally of the car, resulting from heavy buffing or service shocks to which a car is subjected. It will be noted that excessive transverse movement of the table will be prevented by the plates 25 and 26 of the supporting member 16 contacting with the center sill members 5, 5, and that excessive vertical movement in an upward direction will be prevented by the members 22 and 28 contacting with the underside of the side and center sills respectively.

When it is desired to lower the table the operator loosens the nuts 37 and 38 and by the use of a bar or other suitable tool turns the screw members 35 in the direction as indicated by the arrows in Fig. 1, which permits the table to move downwardly until the lower portions of the supporting members 15 and 16 rest on the foundation 12, as shown in dot and dash lines in Fig. 3, at which time it will be noted that the underframe will be entirely relieved of the weight of the table and any load that may be carried thereon.

It may be here noted that the expressions "center sill" and "side sill" are used throughout this description and the following claims in a broad sense as comprehending not only a multiple but a single element which performs the general functions of a sill, and is longitudinally disposed in the underframe. In connection with the table or platform the expression "supporting member" is used in a broad sense as comprehending not only a multiple but a single element.

To brace the table or platform 14 after it has been lowered to the foundation 12 suitable braces 41 are provided, each of which may be connected at one end with the table and at the other end with a member suitably anchored in the foundation 12. For illustrative purposes each of these braces has been shown as comprising rods 42 and 43 which are preferably connected together at their adjacent ends by turnbuckles 44 or other suitable adjusting means. The end 45 of the rod 42 is suitably connected with the platform 14 and the end 46 of the rod 43 is

preferably connected with a shock absorbing mechanism 47 which in turn may be connected with the member 48 which is anchored in the foundation 12. It will be understood 5 that if desired the shock absorbing device may be omitted and the rod 43 made long enough to be directly connected with the member 48.

As many changes could be made in the 10 above construction and many apparently widely different embodiments of this invention could be made without departing from the scope thereof, it is intended that all matter contained in the above description or 15 shown in the accompanying drawings shall be interpreted as illustrative and not in a limiting sense.

Having thus described my invention what I claim as new and desire to secure by Letters Patent is:

1. The combination with a railroad track, of a foundation over which said track passes, a car adapted to be transported over said track, said car comprising an underframe, 25 wheel trucks supporting said underframe, a platform irremovably carried by said underframe, said platform being movable downwardly relative thereto, said platform comprising side girders adapted to rest on said 30 foundation at the sides of said track and a center girder adapted to rest on said foundation intermediate the rails of said track when said platform is lowered.

2. The combination with a railroad track, 35 of a foundation over which said track passes, a car adapted to be transported over said track, said car comprising an underframe having center and side sills, wheels for carrying said underframe, a platform carried by said underframe adapted to be raised or lowered relative thereto, said platform comprising connected center and side girders adapted to rest on said foundation when said platform is lowered, and means for bracing 40 said platform on said foundation.

3. The combination with a railroad track, 45 of a foundation over which said track passes, a car adapted to be transported over said track, said car comprising an underframe, wheels for supporting said underframe, a table carried by said underframe and movable vertically relative thereto, said table comprising connected center and side girders, said center girder being adapted to 50 rest on said foundation intermediate the rails of said track and said girders being adapted to rest on said foundation outside of said rails when the table is lowered.

4. A car having a platform adapted to be 55 lowered to a position of rest on a foundation near the railroad track rails, and means for bracing said platform on said foundation, said means comprising shock absorbing devices.

5. The combination with a railroad track,

of a foundation over which said track passes, a car adapted to be transported over said track and comprising a vertically movable table, said table having center and side girders adapted to rest on said foundation 70 when said table is moved downwardly.

6. The combination with a railroad track, of a foundation over which said track passes, a car adapted to be transported over said track and comprising a vertically movable 75 table, said table having center and side girders adapted to rest on said foundation when said table is moved downwardly, and means for bracing said table on said foundation.

7. In a car, the combination with an underframe comprising center and side sills, of a platform irremovably mounted in movable relation with said underframe, means mounted on said underframe for raising 85 and lowering said platform, and plates secured to said center sills adapted to prevent said platform from moving in a direction longitudinally of the car when in raised position.

8. In a car, the combination with an underframe comprising center and side sills, of a platform irremovably carried by said underframe, said platform having a plurality of supporting members extending below 95 and inclosing portions of said sills.

9. In a car, the combination with an underframe comprising center and side sills, of a table irremovably carried by said underframe and movable vertically relative thereto, said table comprising connected center and side girders, adapted to rest on a foundation near the track rails when the table is lowered.

10. In a car, the combination with an underframe of a table irremovably carried by said underframe and adapted to be raised or lowered relative thereto, said table comprising connected center and side girders adapted to rest on a foundation near the 105 track rails when the table is lowered.

11. In a car, the combination with an underframe comprising center and side sills, of a platform carried by said underframe and movable vertically relative thereto, said 115 platform comprising center and side girders, and means on said girders adapted to engage said sills and limit the upward movement of the table.

12. In a car, the combination with an underframe, of a table carried by said underframe and adapted to be raised or lowered relative thereto, said table comprising connected center and side girders adapted to 120 rest on a foundation near the track rails when the table is lowered, and means on said girders adapted to engage said underframe to limit the upward movement of the table.

13. In a car, the combination with an un-

derframe comprising center and side sills, and a table movably carried by said underframe and comprising a plurality of supporting members, said center and side sills 5 passing longitudinally through said supporting members.

14. In a car, the combination with an underframe comprising center and side sills, and a table carried by said underframe and 10 adapted to be raised or lowered relative to said underframe, said table comprising hollow supporting members adapted to inclose portions of said sills.

15. In a car, the combination with an underframe comprising center and side sills, and a table carried by said underframe and 15 adapted to be raised or lowered relative to said underframe, said table comprising hollow supporting members adapted to inclose 20 portions of said sills, and means in said supporting members adapted to engage with said sills, and limit the upward movement of the table.

16. In a car, the combination with an underframe comprising longitudinally extending 25 sills, of a table carried by said sills adapted to be raised or lowered relative thereto, said table comprising longitudinally extending members adapted to rest on a 30 foundation near the track rails when the table is lowered, and means in said members adapted to engage said sills when the table is raised to limit the upward movement of said table.

35 17. In a car, the combination with an underframe comprising center and side sills, bolsters extending between and secured to said sills, of a table irremovably carried by said sills adapted to be raised or lowered 40 relative thereto, said table being of less length than the distance between said bolsters, the floor of said table being above said underframe when the table is raised.

18. In a car, the combination with an underframe comprising center and side sills, 45 of wheels for carrying said underframe, a table irremovably carried by said underframe adapted to be raised or lowered relative thereto, said table being of less length 50 than the distance between said wheels, the floor of said table being always above said underframe.

19. In a car, the combination with an underframe comprising center and side sills, 55 horizontally disposed plates at the ends of the car secured to said sills and forming

stationary end platforms, and a vertically movable platform mounted on said underframe between said platforms, said movable platform extending transversely for the full 60 width of said car.

20. In a car, the combination with an underframe, of load carrying means irremovably carried by said underframe, said means being movable to a position of rest on a 65 foundation near the railroad track rails, and means for bracing said table or platform on said foundation, said means comprising shock absorbing devices.

21. The combination with a railroad 70 track, of a foundation over which said track passes, a car adapted to be transported over said track, said car comprising trucks and an underframe, said underframe being supported by said trucks and extending continuously therebetween a platform carried by said underframe and movable downwardly relative thereto to a position of rest 75 on said foundation to relieve said underframe and trucks of the weight of said platform and any load carried thereon.

22. The combination with a railroad 80 track, of a foundation over which said track passes, a car adapted to be transported over said track, said car comprising an underframe which extends from end to end of said car, trucks supporting said underframe, a platform carried by said underframe, said platform being movable downwardly relative to said underframe to a position of rest 85 on said foundation to relieve said underframe of the weight of the platform or any load carried thereon.

23. The combination with a railroad 90 track, of a foundation over which said track passes, a car adapted to be transported over said track, said car comprising an underframe which extends from end to end of said car, trucks supporting said underframe, a platform carried by said underframe intermediate said trucks, said platform being movable downwardly relative to said underframe to a position of rest on said foundation to relieve said underframe of the weight of the platform or any load carried 95 thereon.

In testimony whereof I affix my signature in presence of two witnesses.
